UNITED STATES PATENT OFFICE.

FRIEDERICH W. A. BOLDT, OF HAMBURG, GERMANY, ASSIGNOR TO BOLDT & VOGEL, OF SAME PLACE.

MACHINE FOR CAPSULING BOTTLES.

SPECIFICATION forming part of Letters Patent No. 271,304, dated January 30, 1883.

Application filed March 2, 1882. (No model.) Patented in Germany September 4, 1881, No. 18,923; in France January 30, 1882, No. 147,117; in Belgium February 28, 1882, No. 57,192; in England February 28, 1882, No. 961; in Denmark February 28, 1882, No. 512; in Norway February 28, 1882; in Sweden March 6, 1882, and in Austria-Hungary April 22, 1882, No. 8,376 and No. 15,606.

To all whom it may concern:

Be it known that I, FRIEDERICH WILHELM ANTON BOLDT, a subject of the Emperor of Germany, residing at Hamburg, in the German Empire, have invented certain new and useful Improvements in Machines for Capsuling Bottles, of which the following is a specification.

My invention relates to improvements in machines for capsuling bottles in which the capsules are compressed by means of rubber jaws; and the objects of my improvements are, first, to communicate a sliding motion in the direction from the mouth to the bottom of the bottle to the compressing-jaws, and, second, to afford facilities in operating the driving parts of the machine. I attain these objects by the mechanism illustrated in the accompanying drawings, in which—

Figure 1 is a side elevation, and Fig. 2 a front elevation, of the entire machine worked directly by a lever. Fig. 3 is a side view of a machine worked by means of a gear. Fig. 4 is a sectional side elevation of the working parts; and Fig. 5, a front view thereof, partly in a section.

Similar letters refer to similar parts throughout the several views.

The inner part of the ring *a* is provided with curved inclines *a'*, arranged eccentrically to the axis of the ring *a*, which can be turned by means of a lever, *v*, attached to the socket *b*, as shown in Figs. 2 and 5, or by means of a bevel-gear, *d*, attached to the ring *a*, and a bevel-gearied segment, *e*, to which the lever *k* is fastened, as illustrated by Fig. 3. The ring *a*, when operated by the lever *v*, may be provided with a counter-weight, *g*, by which the ring *a* may return automatically into its first position when the lever *v* is left free. The rotation of the ring *a* induces a sliding motion during

the compression in the direction indicated by the arrow in Fig. 4 to the rubber jaws *y*, attached to the levers *z*, which are hinged to the frame *w* of the machine by means of the pins *u*. By turning the ring *a* the inclines *a'*, sliding outside of the free ends of the levers *z*, cause the latter to swing around their fulcrum *u*. This movement effects a compression of the circumference of the capsule, and simultaneously the advancing of the latter in the direction indicated by the arrow, in order to produce a tight and nice fitting to the head of the bottle. The rollers *x* serve to reduce the friction between the levers *z* and the inclines *a'*. The automatical opening of the jaws *y* will be effected by means of the rubber ring *r*.

Having thus fully described my invention, what I desire to claim and secure by Letters Patent is—

1. In a machine for capsuling bottles, the combination of the levers *z*, hinged outside of and rectangularly to the plane of the ring *a*, provided with compressing-jaws *y*, with the ring *a*, provided with inclines *a'*, substantially as and for the purpose specified.

2. In a machine for capsuling bottles, the combination of the ring *a* and the lever *v* with the counter-weight *g*, substantially as described.

3. In a machine for capsuling bottles, the combination of the ring *a*, which actuates the levers *z*, hinged outside of and rectangularly to the plane of the ring *a*, and the gear *d*, with the geared segment *e* and the lever *k*, substantially as set forth.

FRIEDERICH WILHELM ANTON BOLDT.
